UNITED STATES PATENT OFFICE.

RALPH R. BOSTIC, OF LOS ANGELES, CALIFORNIA.

DEEP-WELL PUMP.

Application filed April 14, 1926. Serial No. 101,874.

This invention relates to deep well pumps. The general object of the invention is to provide a pump which is particularly adapted for economical operation for lifting oil from 5 deep oil wells.

Another object of the invention is to provide a deep well pump wherein the pump actuating means comprises two members which are arranged for movement in opposite 10 directions and wherein the parts are so associated that one of the parts acts as a counter-balance for the other part thereby effecting a great saving in power.

Another object of the invention is to provide a deep well pump wherein the sucker rod is made in two or more parts and wherein mechanism is provided to cause simultaneous movement of the parts in opposite directions.

Other objects of the invention will be apparent from the following description taken in connection with the accompanying drawings, wherein:

Fig. 1 is a central sectional view partly in elevation showing my improved pump;

Fig. 2 is a central sectional view through the casing showing a portion of my invention in elevation and a portion in section;

Fig. 3 is a central sectional view showing the racks and pinions used with my invention;

Fig. 4 is an enlarged sectional view showing the lower valve member;

Fig. 5 is a similar view showing the upper valve member;

Fig. 6 is a section on line 6—6 Fig. 3, and

Fig. 7 is a section on line 7—7, Fig. 5.

Referring to the drawing by reference characters, I have shown a casing at 10. Within this casing is shown a tubing 11. This tubing has within it the part constituting my improved deep well pump. Adjacent to the bottom of the tubing 10, I show a working barrel 12 which is provided with a standing valve 13 and an upper valve 14. The specific 40 type of working barrel and valve therein form no part of my invention and a further description thereof is deemed unnecessary.

A sucker rod 15 is connected to the working barrel. This sucker rod comprises two 50 portions, a lower portion 16 and an upper portion 17. The two portions 16 and 17 of the sucker rod are arranged in an enlarged portion 18 of the tubing 11. This enlarged portion 18 may be made from a number of connected parts and in one of these parts, I ar-

range guide members 19 and 20. The sucker rod may include a polished rod if desired.

Each of these guide members 19 and 20 is rabbeted as at 21 and 22 to provide a recess in which racks 23 and 24 are mounted. The rack 23 is connected to the upper portion 17 of the sucker rod while the rack 24 is connected to the lower portion 16 of the sucker rod. The rear portions of the racks are adapted to engage anti-friction members, shown as roller 65 bearing 25.

The teeth on the racks are shown at 26 and these teeth are adapted to engage pinions 27, 28, 29, 30 and 31 which are mounted on shafts 32, 33, 34, 35 and 36. Each of these shafts is 70 mounted in bearings 37 (see Fig. 6) which are held in blocks 38 secured within the enlarged portion of the tubing.

From the foregoing description it will be apparent that when the upper portion 17 of the sucker rod is pushed downwardly the lower portion 16 of the sucker rod will raise to lift the fluid in the tubing 11.

Connected to the upper portion 17 of the sucker rod I show a piston 39 which is shown 80 as provided with packing rings 40 which engages the cylindrical inner portion of the tubing 11. This valve member is pinned to the portion 17 by means of a pin 41. The valve member is shown as provided with passages 42 which are provided with valve seats at the upper portion thereof. These valve seats are adapted to be engaged by valve balls 43. Guards 44 are arranged about the ball valves. 85

Mounted above the piston 39 I show a fixed valve member 45 which has packing rings 46 for engaging the portion 17 of the sucker rod. This valve member 45 is provided with passages 47, ball valves 48, and guards 49 similar to that described in connection with the piston 39. I prefer to make the piston 39 and the valve member 45 in two pieces which may be secured together in any desired manner. It will be understood that other types 100 of piston and valve member may be used if desired, without departing from the spirit of my invention. If desired, I may omit the upper valves.

In operating my improved pump the upper portion 17 of the sucker rod will be moved downwardly and as it moves downwardly the rack 23 acting through the pinions 27, 28, etc., will lift the rack 24 thereby raising fluid in the bottom of the tubing. The portion 17 of 110

the sucker rod will then move upwardly causing the portion 16 of the sucker rod to move downwardly after which the operation will be repeated. After a short interval the 5 height of the fluid raised in the tubing 11 will be such that as the portion 17 moves down the fluid will pass through the passages 42.

The fluid will be trapped by the valves 43 10 and as the piston moves upwardly the fluid will be carried by it. In a short time there will be sufficient fluid above the piston to cause a part of the fluid to pass through the 15 passages 47 in the valve member 45.

As a result of this action fluid will be 20 lifted to a position above the piston 47 when the portion 17 moves downwardly but the fluid above the valve member will not be lifted during this operation. When the portion 25 17 of the sucker rod moves upwardly the fluid above the piston 39 will be raised but there will be no lifting action exerted on the fluid below the piston so that only part of the column of oil will be raised during each movement.

The location in the well of the enlarged 30 portion containing the piston 39 and the racks and pinions may be varied to suit the particular requirements of each installation 35 but the parts will preferably be so arranged that one portion of the sucker rod will act as a counterbalance for the other portion so that during each pumping stroke there will be no need of lifting the entire rod but the portions will be preferably so proportioned that the weight lifted will be proportional to the weight of the fluid being lifted. With my

invention the weight lifted by the working beam on its working stroke or the work performed by other pumping means will be 40 greatly reduced.

From the foregoing description it will be 45 apparent that I have provided a novel deep well pump which can be economically manufactured and which is highly efficient in use.

Having thus described my invention, I claim:

In combination with a well including a casing having a tubing string therein and a two part sucker rod adapted to actuate a barrel plunger, an enlarged section interposed in said tubing string, said sucker rod including an upper and a lower part arranged in said enlarged section, oppositely disposed guide members in said enlarged 55 portion, guideways in said members, a gear toothed rack positioned in each of said guideways, one of said racks being secured to the upper sucker rod part, and the other of said racks being secured to the lower sucker rod 60 part, anti-friction bearings in the wall of each of said guideways against which said racks are adapted to bear, a plurality of gears 65 adapted to mesh with the gear teeth of each of said racks, each of said gears being supported on a shaft and secured thereto, each end of said shaft being adapted to be positioned in an anti-friction bearing, each of said anti-friction bearings being positioned in a boss fixed to the interior of said enlarged section.

In testimony whereof, I hereunto affix my signature.

RALPH R. BOSTIC.
